UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,295,743.

Specification of Letters Patent. Patented Feb. 25, 1919.

Application filed September 3, 1918. Serial No. 252,297.

To all whom it may concern:

Be it known that I, AUGIE L. HANSEN, a citizen of the United States, and a resident of Evanston, in the county of Cook and 5 State of Illinois, have invented certain new and useful Improvements in Acetylene-Lamps, of which the following is a specification.

My invention relates to gas lamps and 10 particularly to improved pyrophoric ignition mechanism therefor.

Although my invention is applicable to different types of gas lamps and to gas burners, it is of particular utility in miners' 15 acetylene cap lamps. Among the important objects of the invention are to provide ignition mechanism which can be readily applied to lamps or burners; to provide such construction that the pyrophoric sparks will 20 be deflected across the path of the gas issuing from the tip orifice; to provide construction which will break up the solid stream of gas from the tip orifice and will spread the gas to offer greater ignition area 25 and range for the pyrophoric sparks; to provide construction by means of which the pyrophoric material can be heated by the ignited flame to dry it in case it should be rendered useless by moisture; to provide 30 construction which will enable operation of the mechanism without contact of the fingers or hand with the serrated pyrophoric material engaging surface; to provide construction which will enable the use of a 35 long pyrophoric material cartridge; and to provide mechanism which can be readily and accurately operated by one hand without removing the lamp from the miner's cap.

The above and other features of the invention are clearly disclosed in the following 40 specification and on the accompanying drawing, in which drawing—

Figure 1 is a front elevational view of a miner's cap lamp,

45 Fig. 2 is a side elevational view with the upper part of the lamp in section on plane 2—2, Fig. 1,

Fig. 3 is a sectional view on plane 3—3, Fig. 2, and

50 Fig. 4 is an enlarged sectional view of the serrated baffle member, on plane 4—4, Fig. 1.

The lamp shown is an ordinary miner's cap lamp comprising the water container 10 and the carbide cup 11 having detachable 55 threaded engagement therewith. The water

tube 12 is secured to the upper and lower walls of the water container and extends down into the carbide cup, the valve rod 13 extending through the water tube, its upper end 14 having threaded engagement in 60 the tube end and the lower end of the valve rod having the valve surface 15 coöperating with the valve seat 16 at the bottom of the water tube. The lever 17 permits turning of the valve rod to control the water 65 flow. A reflector 18 forms the front wall of the water container and the gas tube 19 extends through the bottom wall of the water container to receive the gas from the carbide cup, the outer end of the gas tube extending 70 axially through the reflector and supporting the gas tip 20 which has the small gas orifice 21. The clamp 22 and the hook 23 at the rear of the water container enables the lamp to be supported on a miner's cap in 75 the well known manner.

Describing now the pyrophoric ignition mechanism, a stud 24 extends forwardly from the reflector parallel with and at one side of the tip and on the front end of this 80 stud is pivoted the plate 25 by means of the screw 26.

Between the stud 24 and the tip 20 and above the tip a barrel or tube 27 extends through the reflector and the water container 85 and is secured to the rear wall of the water container. The front end of the barrel terminates just a short distance behind the plane of the plate 25 and the compression spring 28 confined within the barrel between the adjustable screw 29 and the pyrophoric material cartridge 30, the spring tending to press the front end of the cartridge against the plate 25. The plate 25 has the arm 31 extending outwardly therefrom across the reflector edge, and a coiled spring 32 supported on the stud 24 and anchored at its ends to the arm 31 and the barrel 27 tends to rotate the plate to hold the arm 31 against the stop 33 secured to 95 the reflector flange near the top of the lamp. The plate 25 is always in front of the barrel outlet to prevent escape of the pyrophoric material cartridge, and the plate is cut away at 34 so that when the arm is against the stop the gas stream may flow uninterruptedly from the burner tip. However, when the arm or lever is swung downwardly the lower part of the plate will pass in front of the tip outlet. The inner face of the plate has 100

110

the serrations or teeth 35 which, when the lever is released and the plate returned by the spring, rub over the end of the pyrophoric cartridge to cause sparks. The incandescent pyrophoric material particles are thrown by the teeth across the tip outlet into the issuing gas. Also while these sparks are being projected, the plate is in front of the tip outlet and the gas, which would otherwise issue under pressure in a thin stream, is dispersed and spread within the reflector so as to offer a more extended volume to the sparks, and ignition is thus assured without requiring several manipulations of the plate rotating arm.

My improved ignition mechanism has decided advantages over the wheel type igniting mechanism in which a serrated wheel against which pyrophoric material is pressed is turned by the finger or palm. In the first place such wheel becomes moistened by such engagement and when it is moist the pyrophoric material becomes moistened and will not properly function. With my improved mechanism the serrated plate is rotated by an arm, and it and the pyrophoric material are well protected against moisture. However, should the pyrophoric material become moist it can be readily dried and fitted for service by igniting the lamp and rotating the plate to bring it in front of the tip orifice so that the flame will be deflected against the end of the barrel and the pyrophoric material therein, the heat rapidly drying the pyrophoric material. Again, in my improved mechanism, the sparking operation is more uniform, the spring which returns the plate acting always with the same force, whereas with the ordinary sparking wheel which must be rotated by the finger or hand, the operation is erratic. It will also be noted that in my improved mechanism a long barrel is provided in which a long cartridge of pyrophoric material is accommodated. In arrangements of the prior art short cartridges were used which readily jam in the barrel and are soon used up, requiring frequent recharging. With my improved mechanism a lamp can be re-ignited with certainty without removing it from the miner's head.

I do not, of course, desire to be limited to the exact construction, arrangement and operation shown and described as changes are no doubt possible which would still come within the scope of the invention.

I claim as follows:

1. In a gas lamp, the combination of gas generator mechanism, a burner tip for projecting the gas, a reflector surrounding said tip, a shiftable plate supported adjacent said tip and having serrations, a holder, and a pyrophoric cartridge in said holder in the path of said plate, said plate when shifted causing cooperation of its serrations with

said cartridge to produce sparks, and said plate during such shifting being in front of the tip outlet to deflect and spread the outflowing gas to insure ignition thereof by the sparks.

2. In a gas lamp, the combination of gas generator mechanism, a burner tip for projecting the gas, a reflector surrounding said tip, a plate pivoted adjacent said tip and having serrations on its back, a holder, a pyrophoric cartridge in said holder, means for pressing said cartridge against the serrated back of said plate, and means for rotating said plate to cause coöperation of its serrated surface with said cartridge whereby to produce sparks for igniting gas issuing from said tip, said plate normally exposing the tip outlet but adapted upon rotation to be in front of said outlet whereby to deflect the issuing gas laterally.

3. The combination with a gas tip, of a support therefor, a plate shiftable on said support and having serrations, a holder, a cartridge of pyrophoric material in said holder in the path of said plate, and a spring tending to hold said plate normally in position to expose the tip outlet, said plate when shifted causing its serrations to engage with said cartridge to produce sparks, and said plate during such shifting being in front of the tip outlet to deflect and spread the gas issuing from said tip to insure ignition thereof by the sparks.

4. The combination with a gas tip, of a reflector surrounding said tip, a plate pivoted adjacent said tip and having serrations on its rear side, a holder, a cartridge of pyrophoric material in said holder, means for pressing said cartridge against the serrated side of said plate, a spring tending to hold said plate in normal position against rotation, said plate when rotated causing its serrated face to engage with said cartridge to produce sparks to ignite gas issuing from said tip, and an extension on said plate for passing in front of the tip outlet when the plate is rotated whereby the issuing gas is deflected laterally.

5. In a gas lamp, the combination with a gas tip, of a reflector surrounding it, a plate pivoted on the reflector adjacent said tip and having serrations on its rear side, a barrel, a cartridge of pyrophoric material in said barrel, a spring in said barrel pressing said cartridge against the rear side of said plate in the path of serrations thereon, an actuating arm on said plate, a stop on said reflector, a spring tending to hold said arm against said stop, said arm when swung away from said stop causing rotation of said plate, and return of said arm by said spring causing reverse rotation of said plate and engagement of its serrations with its cartridge to produce sparks for igniting gas issuing from said tip.

6. In a gas lamp, the combination with a gas tip, of a reflector surrounding it, a plate pivoted on the reflector adjacent said tip and having serrations on its rear side, a barrel, a cartridge of pyrophoric material in said barrel, a spring in said barrel pressing said cartridge against the rear side of said plate in the path of serrations thereon, an actuating arm on said plate, a stop on said reflector, a spring tending to hold said arm against said stop, said arm when swung away from said stop causing rotation of said plate, and return of said arm by said spring causing reverse rotation of said plate and engagement of its serrations with its cartridge to produce sparks for igniting gas issuing from said tip, said plate normally clearing the tip outlet but being in front of said outlet during rotation whereby to deflect laterally the gas issuing from said tip.
7. The combination with a gas tip, of a reflector surrounding it, a plate pivoted adjacent to and at one side of said tip to rotate in a plane in front of the tip, a barrel, a cartridge of pyrophoric material within said barrel, a spring in said barrel pressing said cartridge against the rear face of said plate, a stop on said reflector, a spring normally holding said plate against said stop, serrations on the rear side of said plate, said serrations coöperating with said cartridge during rotation of the plate to form sparks for igniting gas issuing from said tip.
8. The combination, with a gas tip, of a reflector surrounding it, a plate pivoted adjacent to and at one side of said tip to rotate in a plane in front of the tip, a barrel, a cartridge of pyrophoric material within said barrel, a spring in said barrel pressing said cartridge against the rear face of said plate, a stop on said reflector, a spring normally holding said plate against said stop, serrations on the rear side of said plate, said serrations coöperating with said cartridge during rotation of the plate to form sparks for igniting gas issuing from said tip.
9. The combination with a gas tip, of a concave reflector surrounding it, a plate pivoted on the reflector adjacent to and at one side of the tip to rotate in a plane in front of the tip, a holder supported adjacent said tip, a cartridge of pyrophoric material within said holder, a spring pressing said cartridge against the rear face of said plate, an arm extending from said plate whereby it may be rotated, a stop on said reflector, a spring tending to hold said arm against said stop, said serrations coöperating with the cartridge when the plate is rotated to cause sparks for igniting gas issuing from said tip.
10. In an acetylene miner's lamp comprising a water container, a carbide cup, a reflector at one end of said water container, a gas outlet surrounded by said reflector, a plate pivoted on the reflector adjacent the outlet to rotate in the plane in front of the outlet, the rear face of said plate being serrated, a barrel extending through said water container and reflector, a cartridge of pyrophoric material in the front end of said barrel, a spring within the barrel pressing said cartridge against the serrated face of said plate, the serrations on said plate coöperating during rotation of the plate with said cartridge to produce sparks for igniting gas issuing from said outlet.

In witness whereof, I hereunto subscribe my name this 27th day of August, A. D., 1918.

AUGIE L. HANSEN.
